TRANSPORTATION BOX FOR BABY CHICKS

Kinney I. Miller, Lancaster, Mo.

Application August 14, 1944, Serial No. 549,347

4 Claims. (Cl. 229—6)

1

My invention relates to a transportation box for baby chicks.

There exists a large industry in the shipment of baby chicks and the like. Baby chicks and other small poultry are quite delicate and great care must be taken in shipping them. Many of the boxes used commercially for this purpose have ordinary flat bottoms. In shipment these flat bottom boxes may be placed on a damp platform or in the snow or on a hot concrete floor. In either of such contingencies the baby chicks may be injured by cold or heat. Also it sometimes occurs that baby chicks are stacked with the flat bottom of one placed on the flat top portion of another box in such a way as to close the ventilation holes in the top of the lower box.

It is an object of my present invention to provide a box which will eliminate all of the bad features mentioned above by providing means for raising the bottom of the box slightly above the surface on which the box rests.

In accomplishing my purpose, it is also my object to utilize quite a number of features of construction which are already in practical commercial use in my boxes. In such boxes particularly I may employ the rib structures such as are shown on the lids of the boxes in my Patent No. 2,320,245, issued May 25, 1943, except that the ribs are placed on the bottom of the box instead of on the top. This enables me to utilize certain dies and die processes and methods, and experience of manufacture already available in the chick transportation boxes which I have produced by the modification and further improvement over my previous box. The bottom has ribs which support the box and lift the bottom on which the chicks are supported to a level above the surface on which the box rests. The ribs whereby the bottom of the box is thus raised, are such as to afford troughs on the inside of the box and it is therefore desirable to provide a false bottom. Heretofore it has been the common practice to use in chicks boxes excelsior pads or the like which give the chicks a firm footing so that they will not slide into one corner if the box is tipped a little, and which also afford absorbent material for the droppings. Where my improvement of the present invention is used, these excelsior pads will be omitted and I use instead a thin false bottom of corrugated paper with liner on the underside only.

It is also my purpose to provide, at least optionally, similarly arranged ribs at the sides of my improved box which function for ventilation and also to keep the box spaced from other boxes

2

or any wall or the like which might shut off the holes at the sides of the box.

Certain details which are of some importance to my present invention will appear as the description proceeds.

With these and other objects in view, my invention consists in the construction, arrangement and combination of the various parts of my device whereby the objects contemplated are attained, 10 as hereinafter more fully set forth, pointed out in my claims and illustrated in the accompanying drawing, wherein:

Figure 1 is a plan view of a blank sheet of heavy cardboard from which my improved chick box 15 may be made.

Figure 2 is a top or plan view of the box made from the blank shown in Figure 1, and

Figure 3 is a side elevational view of the box.

My improved chick box is preferably made from 20 heavy cardboard into a carton-like box. The features of the improvements are such that the box may be made very cheaply and inexpensively by stamping blanks such as that shown in Figure 1 and indicated generally by the reference numeral 1.

In the showing of the blank 1, the dotted lines within the outline indicate creases and the full line indicates slits. In the blank, the portions 2 ultimately form the ends of the finished box. 30 These ends 2 have end flaps 3. Each end flap 3 is connected to its end at the creased line 4. Each end flap is severed from that portion of the blank which is intended to form a side of the box as indicated at the slit or cut 5. Each end member is connected along the creased line 6 with the portion of the blank forming the bottom of the box.

At 7—7—7—7 I have indicated the points which are at the corners of the bottom of the completed box. The area within the four corners 7 forms the bottom of the completed box and is indicated at 8.

At 9—9—9—9 I have indicated the points which will be at the top corners of the completed box. Thus it will be seen that the area within the four corners 9—9—9—9 at the top of Figure 1 and the

45 area within the four corners 9—7—7—9 at the bottom part of Figure 1 are intended to form the sides of the completed box. Each of these side areas 9 is connected to the bottom area 8 along lines which are creased at 11, 12, 13, 14, 15 and 16 and slit at 17, 18, 19 and 20.

I shall now describe the arrangement and construction of the blank which permits the provision of the ribs on the bottom of the finished box and at the sides of the finished box. Each blank is creased from one side to the other along

the parallel lines 21. Each blank is also creased along lines 22, 23, 24 and 25 from the side edges inwardly into the bottom area 8. Between the inner ends of the lines 22 and 23, the paper of the blank is slit as at 26. Between the inner ends of the creased lines 24 and 25, the material of the blank is slit at 27. The material is also slit from the ends of the slit 26 and at right angles thereto and extending to the adjacent creased line 21, as indicated at 28-28. The material is also slit from the ends of the slit 27 and at right angles thereto by slits 29, 29 extending to the adjacent creased line 21.

The material bounded by the slits 26 and 28 and one of the creased lines 21 is indicated at 30 and forms a tongue connected to the bottom 8 along one edge in the creased line 21. The purpose of this tongue will later appear. The material bounded by the slits 29, 27, 29 and a part of one of the creased lines 21 forms a similar tongue 30. The blank is creased along the lines 31, 32, 33, 34. Thus the crease 31 extends from the side of the blank to the slit 28. The creased line 32 extends from the lower side of the blank to the lower slit 28. The crease line 33 extends from the top of the blank to the upper slit 29, and the crease line 34 extends from the lower edge of the blank to the lower slit 29.

The area bounded by the slit 29, crease line 22, slit 18 and crease line 21 ultimately forms a rib on the bottom of the completed box. A similar rib is formed by that area of the blank bounded by the lower slit 28, the crease line 23, the slit 17 and the crease line 21. Another such rib is ultimately formed by the area bounded by the slit 20, crease line 21, upper slit 29 and the crease line 24. Finally another such rib is ultimately formed on the bottom by the area bounded by the crease line 21, the slit 18, crease line 25 and the slit 29. While I have shown provision for two ribs on the bottom of the box, it will be understood that more may be used if desired.

In the side-forming portions 10 of the blank, parts are cut away at 35 in the top and bottom of the blank to leave notches as shown. The parts of the blank indicated at 36 ultimately form the ribs on the sides of the box. The sides 10 and the ends 2 may be provided with knock-outs 37 which, in use of the box, may be punched out to the extent they may be desired for affording ventilation.

I shall now describe the process of forming the box from the blank. This description is illustrative only.

The tongues 30 are raised slightly along hinge lines so as to be out of the plane of the blank. The blank is then bent along the lines 31 and 32 and 33, 34 to form a downwardly extending rib R on the bottom of the box, see Figure 3. The free edges of the tongues 30 will then overlap a part of the box bottom and these overlapping portions are fastened to the box bottom by staples as indicated at 38. The sides 10 are bent to upright position. Each side will then have a pair of ribs R-1 as shown in the top view of Figure 2. It will be noted that by the provision of the cut-out portions 35 heretofore mentioned, the ribs R-1 terminate short of the top of the box so that they do not interfere with putting an ordinary lid on the box. The ends 2 are then bent up and the end flaps are bent to overlap the sides 10 as shown in Figure 2 and are stapled to the sides 10 as indicated at 39. The end flaps

3 overlap the sides 10 to the ribs R-1 and serve to brace the box and cause it to retain its proper shape.

The ribs R serve to support the box with its top in raised position. The tongues 30 however being stapled hold the ribs R against spreading.

The side ribs R-1 are provided with knock-outs 40 which afford ventilation and will be again referred to. The ribs R in the bottom of the box form troughs. Unless these are covered up, the baby chicks might crowd into the trough and smother each other. I therefore put into the completed box a false bottom indicated at 41, made up of corrugated paper with a liner on its underside, and which covers the troughs formed by the ribs R and affords a rough bottom for the box so that the chicks will not slip or slide into the corners, and also affords absorbent material. This false bottom 41 does away with the need for asbestos pads.

My improved chick box is of such structure that the ribs R hold the box above the surface on which it rests. They keep the box off the cold floor in cold weather and keep it off hot pavements and permit ventilation under it in warm weather. They utilize available equipment and known processes of manufacture, so that they can be economically provided.

The ribs R-1 at the sides of the box afford 30 ventilating flues which admit air to the box but deflect it in entering so that it does not flow directly on the chicks. The knock-outs 40 can be knocked out to afford further ventilation if desired and the air coming in through these 35 openings is not so likely to blow directly on the chicks as that entering through ordinary ventilation holes. It has been noted that the ribs R-1 terminate at their upper ends at such a height as to permit proper ventilation without 40 interfering with the installation of the box cover. By providing the side ribs R-1 in line with the bottom ribs R, the cost of die making is kept down.

45 It will of course be understood that the box is intended to be used with an ordinary cover not here shown. Such covers may be flat so that a series of the boxes may be stacked, even when filled with chicks, to thus conserve space without 50 any substantial interference with the ventilation of the boxes.

Some changes may be made in the details of the construction of my improved box and it is my intention to cover by my claims any such 55 modifications as may be reasonably included within the scope of my invention.

I claim:

1. In a box for shipping young chicks, a bottom having transverse portions shaped to form downwardly projecting ribs, and having tongues for securing together the parts of the box bottom on opposite sides of the ribs, said box having sides with similar ribs, aligned with the respective bottom ribs, terminating short of the top 60 of the box a sufficient distance to avoid interference with the use of a flanged cover and forming ventilating flues and means to space other articles from the box.

2. In a box for shipping young chicks, a bottom having transverse portions shaped to form downwardly projecting ribs, and having tongues for securing together the parts of the box bottom on opposite sides of the ribs, said box having sides with similar ribs, aligned with the respective bottom ribs, terminating short of the 70 75

top of the box and forming ventilating flues and means to space other articles from the box, said box having ends, with flaps overlapping the sides to the adjacent side ribs, to brace the ribs.

3. A box for shipping young chicks, having sides with outwardly projecting vertical ribs bent from the box material, to form flues and spacing elements but terminating short of the top to avoid interference with the flanged cover, said box having ends with flaps overlying the sides substantially to the side ribs to brace the ribs.

4. A box for shipping young chicks, having sides with outwardly projecting vertical ribs bent from the box material to form flues and spacing elements said ribs terminating short of the top.

of the box to avoid interfering with the flange of a flanged cover for said box.
